US0D1036992S

(12) **United States Design Patent** (10) **Patent No.:** **US D1,036,992 S**
(45) **Date of Patent:** **** Jul. 30, 2024**

(54) **CLOSURE FOR CONTAINERS**

(71) Applicant: **LIVINGPACKETS SA**, Pully (CH)

(72) Inventors: **Amaury Godec**, Nantes (FR); **Charles Colas**, Nantes (FR)

(**) Term: **15 Years**

(21) Appl. No.: **35/515,943**

(22) Filed: **Jul. 13, 2022**

(80) **Hague Agreement Data**

Int. Filing Date: **Jul. 13, 2022**

Int. Reg. No.: **DM/223280**

Int. Reg. Date: **Jul. 13, 2022**

Int. Reg. Pub. Date: **Jan. 13, 2023**

(30) **Foreign Application Priority Data**

Jan. 17, 2022 (CH) 2022-00029

(51) **LOC (14) Cl.** **09-07**

(52) **U.S. Cl.**

USPC **D9/443; D9/435**

Primary Examiner — Darcey E Gottschalk

(57) **CLAIM**

The ornamental design for a closure for containers, as shown and described.

DESCRIPTION

4. Closure for containers

5. Closure for containers

8. Closure for containers

9. Closure for containers

4.1 : Perspective

4.2 : Perspective

4.3 : Front

4.4 : Back

4.5 : Top

4.6 : Bottom

4.7 : Left

4.8 : Right

4.9 : Enlarged perspective

4.10 : Enlarged front

4.11 : Enlarged top

4.12 : Enlarged bottom

4.13 : Enlarged left

4.14 : Enlarged right

5.1 : Perspective

5.2 : Perspective

5.3 : Front

5.4 : Back

5.5 : Top

5.6 : Bottom

5.7 : Left

(Continued)

8.1 : Closure for containers exploded perspective view
8.2 : Closure for containers exploded perspective view
8.3 : Closure for containers exploded front view
8.4 : Closure for containers exploded back view
8.5 : Closure for containers exploded top view
8.6 : Closure for containers exploded bottom view
8.7 : Closure for containers exploded left view
8.8 : Closure for containers exploded right view
8.9 : Closure for containers enlarged exploded perspective view
8.10 : Closure for containers enlarged exploded front view
8.11 : Closure for containers enlarged exploded back view
8.12 : Closure for containers enlarged exploded top view
8.13 : Closure for containers enlarged exploded left view
8.14 : Closure for containers enlarged exploded right view
9.1 : Perspective
9.2 : Perspective
9.3 : Front
9.4 : Back
9.5 : Top
9.6 : Bottom
9.7 : Left
9.8 : Right
9.9 : Enlarged perspective
9.10 : Enlarged top
9.11 : Enlarged left
9.12 : Enlarged right

The evenly-sized broken lines illustrate portions of a container that form no part of the claimed design, and the long-short broken lines illustrate reference lines for the enlarged views and form no part of the claimed design.

1 Claim, 53 Drawing Sheets
